UNITED STATES PATENT OFFICE.

JAMES M. SPRINKEL, OF AURORA, ILLINOIS.

STEAM BOILER.

Application filed August 23, 1920. Serial No. 405,374.

To all whom it may concern:

Be it known that I, JAMES M. SPRINKEL, a citizen of the United States, residing at Aurora, in the county of Kane and State of Illinois, have invented a certain new and useful Improvement in Steam Boilers, of which the following is a specification.

My invention relates to steam boilers and is adapted more particularly for high pressure operation in steam driven motor vehicles. One of the disadvantages of steam driven road vehicles such as trucks and automobiles is that they are operated at high pressure and that a great deal of water of necessity passes through them in comparison to the size of the boiler. Furthermore, it is frequently necessary to use water in which there is a good deal of solid matter in suspension, as a supply of good water is not always available. The result is that usually sediment rapidly collects in such boilers, and after a half inch or so of sediment has collected at the bottom, and baked hard, the heat of the flue gases burns out the tubes. One of the objects of my invention is to remedy this difficulty by providing a boiler in which the heads and tubes may be readily removed from the shell, or vice versa, for cleaning purposes. In other words, one of the objects of the invention is to provide a practical "take down" boiler. Another object is to promote thermal efficiency by providing a jacket or outer chamber from which the air may be exhausted, to thus insulate the boiler from the surrounding atmosphere and reduce the loss through radiation. Still another object of the invention is to form a mud trap in which the sediment will tend to collect and from which it may be drawn from time to time without necessitating taking the boiler apart.

I accomplish my objects by the construction illustrated in the accompanying drawing in which—

Figure 1 is a top view of the complete boiler;

Figure 2 is a sectional view on the line 2—2 Figure 1 and

Figure 3 is a fragmentary detail showing in section a suitable type of gasket and grooves for producing a tight connection between the shell and the heads.

Like numerals denote like parts throughout the several views.

In the form selected to illustrate the invention, the boiler has fire tubes 1 which are arranged vertically and terminate at their upper and lower ends in the boiler heads 2, 3. The tubes are permanently fastened to the heads and convey the flue gases through them and through the body of the boiler. The sides of the boiler are formed by a main shell 4, which, by preference, is reinforced by annular steel bands 6. At the foot of the shell is a flange 8 which extends outward and makes surface contact with the flange 2^a at the circumference of the lower head. These flanges are detachably secured together by bolts 10. In order to insure steam tight connection, it is desirable to interpose copper gaskets 12 in the manner shown in detail in Figure 3. In this case, opposed grooves 14 are formed in the flanges and a copper gasket is employed which is of somewhat larger diameter than the width of the grooves. The result is that when the flanges are forced together, the gasket automatically conforms more or less completely to the configuration of the grooves and an effective joint is produced.

At the upper end, the shell encircles the upper head 3 and has a flange 16 which extends inward so as to make contact with the upper surface of the head at the peripheral margin thereof. These parts are also detachably secured together by bolts 10 and gaskets 12.

A mud trap is formed in the lower head and by preference assumes the form of an annular depression 18 located just inside of the shell. Screw plugs 20 screw into this depression at the bottom and by unscrewing them the boiler may be washed out, and the sediment removed.

Surrounding the main boiler shell is an outer shell 24 which is preferably of thinner gauge material, as it is not, in practice, subjected to any great degree of strain. While the shell may be formed in various ways, it is desirable to make it in the form of an ordinary cylinder open at the lower end so as to make a drive fit with the rim of the flange 8 and with an inward projecting flange 26 at the upper end which enables it to make a drive fit with the sides of the boiler shell near the top.

A pipe 28 extends upward from the upper boiler head for leading the steam to the point where it is to be used.

In practice, when the parts are assembled as shown, the major portion of the air is withdrawn from the outer shell or jacket 24 which creates a so-called vacuum there-in, and effectively insulates the boiler so that the loss by radiation is reduced to a minimum. Ordinarily, most of the sediment can be removed by unscrewing the plugs 20 and washing out the interior of the boiler. Scale, however, cannot so readily be removed, and when a more thorough cleaning is desirable, the various bolts 10 are removed, whereupon the shell 4, and with it the outer shell 24, can be lifted off bodily, thus exposing the tubes and the inner sides of the heads so that they may be thoroughly cleaned. The inside surface of the boiler shell 4 is also thus made accessible so that any scale which may be deposited on it can also be removed. After the insides of the boiler have thus been cleaned, the shell may be again lowered into position over the upper head, after which the parts may be bolted together and the boiler once more put into service. It will be noted that as a result of this construction, it does not become necessary to disturb the fire tubes in any way nor to disturb the upper or lower heads nor the piping which in practice is connected to them. Nor is it necessary to remove the outer shell 24, as it virtually becomes a part of the inner shell and may at all times stay with it, consequently it is not necessary to re-create the vacuum within the outer shell every time the shell is removed for cleaning purposes.

It will be seen that in the form shown, the gaskets are placed between two pairs of surfaces which, when the shell is being positioned, approach directly toward each other—that is, the shell flanges do not approach the heads tangentially, but perpen-

dicularly to them. The movement is normal to the plane of the heads. This makes it possible and practicable to introduce gaskets between the cooperating surfaces, and these may be as large as desired. It is even possible to employ two gaskets at each joint instead of one, as shown.

Having thus described my invention, what I claim as new and desire to secure by Letters Patent, is:

In a device of the class described, a lower head, an upper head of less diameter than the lower head, tubes having their ends mounted in the heads, an inner shell surrounding the upper head and provided at its upper end with an inwardly extended annular flange overlapped on the outer surface of the upper head, the shell being provided at its lower end with an outstanding annular flange resting on the lower head, the periphery of the said flange being spaced from the periphery of the lower head to form a shoulder, securing devices connecting the first specified flange of the shell with the upper head, securing devices connecting the last specified flange of the shell with the lower head, an outer shell resting on the shoulder and engaged with the periphery of the last specified flange, the outer surface of the outer shell being substantially flush with the outer edge of the lower head, the outer shell being provided at its upper end with an inwardly extended flange engaging the inner shell in a plane substantially coincident with the upper head, the lower head being provided with an annular depression located closely adjacent to the inner shell, and means for draining the depression.

In witness whereof, I have hereunto subscribed my name.

JAMES M. SPRINKEL.
